STONE FOR COSTUME JEWELRY OR SIMILAR ARTICLE

Adolph Katz, Providence, R. I., assignor to Coro, Inc.,
New York, N. Y., a corporation of New York

Application October 25, 1955, Serial No. 38,551

Term of patent 7 years

(Cl. D45—1)

Fig. 2

Fig. 1 is a plan view of a stone for costume jewelry or similar article showing my new design.

Fig. 2 is an edge view thereof.

I claim:

The ornamental design for a stone for costume jewelry or similar article, substantially as shown.
